UNITED STATES PATENT OFFICE.

MARY E. VERDIER, OF PITTSBURG, PENNSYLVANIA.

SOAP-SAVING DEVICE.

SPECIFICATION forming part of Letters Patent No. 594,664, dated November 30, 1897.

Application filed January 12, 1897. Serial No. 618,961. (No model.)

To all whom it may concern:

Be it known that I, MARY E. VERDIER, a citizen of the United States of America, residing at Pittsburg, in the county of Allegheny and State of Pennsylvania, have invented certain new and useful Improvements in Soap-Saving Devices, of which the following is a specification, reference being had therein to the accompanying drawings.

10 This invention relates in general to toilet articles, and more particularly to that class known as "soap-saving devices."

The invention has primarily for its object to provide new and novel means whereby it 15 will be possible to greatly economize in the use of soap. Furthermore, to design a device of the above-referred-to class that will be highly attractive, effectual in its operation, and comparatively inexpensive to manufacture.

20 A further object of my invention is to construct a device that will guard against soap being carried away from public wash-rooms and the like. A still further object to provide means whereby soap will be made to 25 float upon the surface of the water and when sufficiently used suspended by a chain or cord.

With the above and other objects in view 30 the invention finally consists in the novel construction, combination, and arrangement of parts, to be hereinafter more particularly pointed out, and specifically described in the claim.

35 In describing the invention in detail reference is had to the accompanying drawings, forming a part of this specification, and wherein like letters of reference indicate similar parts throughout the several views, 40 in which—

Figure 1 is a vertical sectional view of my improved soap-saving device. Fig. 2 is a vertical sectional view of a piece of soap. Fig.

3 is a transverse sectional view of the same. 45 Fig. 4 is a front elevation of a piece of soap.

In the drawings, A indicates a casing made in two or more sections and removably fastened together having an outwardly and

downwardly extending portion B. The underneath face of said portion B is apertured 50 at b². Pulleys C C are suitably journaled within the outwardly-extending portion b.

The reference-letter D indicates a chain or cord passing through the opening b² and over the pulleys C C. The end of said chain within 55 the casing is attached to a counterbalance-weight E. The other end of the chain carries a suitable lock F, to which is secured a piece of soap. (Indicated by reference-letter G.)

A hollow float H carries on one end a stem h, which terminates in a loop h'. The piece of soap is so formed as to cover the float, the loop h' being the only portion that will protrude, said loop being adapted to engage the 65 lock carried by the chain. Preferably a receptacle or basin J is attached on the outer face of the casing directly in alignment with the chain.

The operation of my improved soap-saving 70 device will be apparent from the foregoing description when taken in connection with the several views of the drawings.

The counterbalance-weight should equal the weight of the soap, in order that the latter 75 may easily return to a suspended position when not in use; furthermore, to relieve the strain that would otherwise be caused in case of a heavy weight to the chain.

Particular attention is called to the fact 80 that the soap will always float on the surface of the water and may be easily returned to a suspended position, the basin serving to receive the drippings.

It will be noted that various changes may 85 be made in the details of construction of my improved soap-saving device without departing from the general spirit of invention. For example, a spring may be substituted for the weight, and the device will perform 90 the same functions.

Having fully described my invention, what I claim as new, and desire to secure by Letters Patent, is—

In a soap-saving device, the combination of 95 a sectional casing provided with an outward

and downward extension, pulleys mounted in the upper part of said extension; over which a chain is operated, and passing through an opening in lower part of said extension, the 5 chain carrying on one end a counterweight, and on the other end a lock connecting a piece of soap, a float provided with a stem carrying an eye, and a coating of soap covering

said float, substantially as shown and described.

In testimony whereof I affix my signature in presence of two witnesses.

MARY E. VERDIER.
